Inventor,
C. H. Grings, by
G. C. Kennedy,
Attorney.

UNITED STATES PATENT OFFICE.

CASPER HUGO GRINGS, OF WATERLOO, IOWA.

BUCKLE.

1,341,315.

Specification of Letters Patent.

Patented May 25, 1920.

Application filed September 13, 1919. Serial No. 323,510.

To all whom it may concern:

Be it known that I, CASPER HUGO GRINGS, a citizen of the United States of America, and a resident of Waterloo, Blackhawk county, Iowa, have invented certain new and useful Improvements in Buckles, of which the following is a specification.

My invention relates to improvements in buckles, and particularly to that class of buckles which are provided with lever tongues, and the object of my improvement is to supply for any description of buckle frames, whether plain or ornamental, having a tongue bar, a lever tongue having means for pivotally mounting it on the tongue bar with an interspace or clearance between it and the tongue bar permitting free seating and attachment of the leather holding piece to the tongue bar, and whereby the tongue may freely move without binding or interference.

This object I have accomplished by the means which are hereinafter described and claimed, and which are illustrated in the accompanying drawings, in which Figures 1 and 2 are respectively a plan and a side elevation of my improved combined lever tongue and tuck loop with bifurcated bearing projection; Figs. 3 and 4 are plans of different designs of buckle frames; Fig. 5 is a perspective view of my combined lever tongue and tuck loop as pivotally mounted upon the tongue bar of the buckle frame shown in said Fig. 3; Fig. 6 is a plan of one end of a strap, slotted and divided into a pair of terminal members before assembling with my improved buckle; Fig. 7 is a plan of said divided strap end as assembled with my said buckle, and Fig. 8 is a side elevation of said assembled parts, showing the end part of another strap connected to said buckle parts and secured to the lever tongue thereof.

Similar numerals of reference denote corresponding parts throughout the several views.

Any description of buckle frame may be used in conjunction with my improved combined lever tongue and tuck loop, wherein a tongue bar 9 is furnished upon which to pivotally mount the tongue member 5. The frame shown in Fig. 4 is of an ornamental design suited for some purposes where display is desired, and any other ornamental configuration of the frame ele-

ments 8, 9 and 11 may be adopted. In Fig. 3 is shown a preferred type of buckle frame, whose elements 8, 9 and 11 are such as to provide a hollow rectangular frame, the forward bar 11 having a sleeve 12 mounted thereon, and the tongue bar 9 having a pair of spaced lugs 10 positioned medially on its outer edge, the interspace of the lugs used as a medial bearing for a tongue 5 pivoted thereon.

The tongue 5 has an integral tuck loop 2 projecting therefrom oppositely and preferably curved upwardly to seat it with its side members 2 depending over the side edges of a received strap end 17 with the cross bar 1 resting upon the top of the strap, which thus binds the parts together to prevent any side movements of the tuck loop. The cross bar 3 of the tuck loop from whose forward edge the tongue 5 projects is widened at 4 to strengthen it and afford a supporting body for a downwardly extending bifurcated integral projection 6, flattened in the medial plane of the tongue and tuck loop. The curved bifurcations 7 of said projection may be clenched around the middle of the tongue bar 9 between the lugs 10, as the tongue bar element may be made of malleable iron or other material capable of being bent without fracture. This construction and means of connecting the tongue bar to the lever tongue is best shown in Fig. 5.

In order to mount said buckle on a strap 13, the strap is provided with a medial longitudinal slot 15 at some distance from one end, wide enough to allow of insertion of the projection 6. The strap is then split from said slot toward said end to provide a pair of separated end members 14. It will be particularly observed that the projection 6 is made long enough, as is shown in the Figs. 2, 5 and 8, to provide a relatively wide interspace or clearance between the tongue bar 9 and the combined and alined tongue 5 and tuck loop 2, sufficient to freely permit passage and reception of the strap members 14 about the stem 6, to receive said projection in and through the slot 15, the members 14 then being bent reversely around the tongue bar 9 and positioned in contact with the under surface of the strap 13, and secured thereto by rivets 16 or other fastening means as may be desired.

This wide clearance permits the tongue to

swing freely on the tongue bar, and this construction is very efficacious in the manufacture and assemblage of said parts.

Fig. 8 shows the end of another strap 17 secured removably to said improved buckle, the strap having orifices as usual to receive the tongue 5 adjustably after the strap has been passed through the buckle frame, and the extremity of said strap 17 is then passed 10 through the tuck loop 2, the cross bar 1 resting on the strap and a leverage being exercised thereby on the tongue 5 to hold the latter close to or in contact with the buckle frame, with the side bars 2 of the 15 tuck loop positioned along or across the side edges of the strap parts 17 and 13, preventing side play of the buckle.

Various minor changes may be effected in the forms and arrangements of the parts of 20 my said buckle, without, however, departing from the scope or principles of my invention.

Having described my invention, what I claim as new, and desire to secure by Letters 25 Patent, is:

1. In a device of the character described, an independent buckle frame provided with a tongue bar, and a tongue member having a bifurcated projection adapted to be pivotally mounted on the tongue bar with the bifurcations clenched around the tongue bar.
2. In a device of the character described, an independent buckle frame provided with 30 a tongue bar, and a tongue member con-

sisting of a combined single tongue and a tuck loop, said tongue member having an integral bearing projection mounted pivotally on the central portion of said tongue bar, and said tongue bar having means thereon for preventing side play of said tongue. 40

3. In a device of the character described, an independent buckle frame provided with a tongue bar, a tongue member consisting of 45 a combined single tongue and an upwardly curved tuck loop, said tongue member having an integral projection provided with a bearing opening pivoted on said tongue bar, the projection being lengthened to afford 50 clearance between said tongue bar and said combined tongue and tuck loop for passage of a strap therebetween.

4. In a device of the character described, in combination, an independent buckle 55 frame provided with a tongue bar, a tongue member consisting of a combined single tongue and a tuck loop, said tongue having a lengthened projection pivotally mounted centrally on said tongue bar, with the combined tongue and tuck loop spaced from the tongue bar, and a strap having one end longitudinally divided, its members passed about said projection through said interspace, around the tongue bar and then fastened to the undivided part of the strap. 60

Signed at Waterloo, Iowa, this 10th day of September, 1919.

CASPER HUGO GRINGS.
